UNITED STATES PATENT OFFICE.

HENRY WILLIAM FRACKMANN, OF PHILADELPHIA, PENNSYLVANIA.

RUNNING-GEAR FOR VEHICLES.

SPECIFICATION forming part of Letters Patent No. 414,693, dated November 12, 1889.

Application filed November 15, 1887. Serial No. 255,279. (No model.)

To all whom it may concern:

Be it known that I, HENRY WILLIAM FRACKMANN, a citizen of the United States, residing at Philadelphia, in the county of Philadelphia and State of Pennsylvania, have invented an Improved Metallic Anti-Friction Running-Gear or Truck for Wagons with Fifth-Wheel Combined, of which the following is a specification.

10 My invention relates to improvements in wagon running-gears or trucks in which combination of materials are avoided and the friction of the movable parts is reduced to a minimum. Generally iron and wood are used, but as the expansion and contraction of the two materials are so different it is impossible to combine them satisfactorily, and therefore unsafe. Besides this, a metallic running-gear or truck can be made in less time than a composite gear, hence cheaper. I obtain this by using only one kind of material—brass, iron, steel, or any other suitable metal. The sectional shape may be bar, angle, channel, or tubular form. The construction of the 25 same is illustrated in the accompanying drawings and the specification.

Figure 1 is a plan view of the running-gear or truck with fifth-wheel combined for wagons where poles or shafts are required. Fig. 30 2 is a side view, and Fig. 3 a back view, of Fig. 1. Fig. 4 is a plan view of running-gear or truck with fifth-wheel combined for wagons with shafts only. Fig. 5 is a cage containing friction-rollers to move between the 35 upper and lower part of the fifth-wheel. Fig. 6 is a vertical section through Fig. 5.

The parts A, B, and C are bent to suitable form required, whereby the middle portion of A forms a part of the fifth-wheel. These 40 parts are fastened together with plates *a* and *b*. The pieces C, also parts of the fifth-wheel, and the front bar C' are fastened to B, which latter pieces likewise carry the receptacle for the king-bolt. Plates *d*, Figs. 1 and 2, are 45 secured to B, and form also with the same the pocket for the pole. The back piece D is fastened to A and B and receives the back spring, to which the side springs are connected. It is readily seen that with a few 50 pieces a strong yet light running-gear or truck can be constructed with fifth-wheel combined,

difference in temperature having no effect. Fig. 4 is a similar metallic running-gear or truck with fifth-wheel combined, but only for lighter wagons provided with shafts. It will 55 be seen that the middle pieces B are closed together with the plates *d*; then they widen out, so as to receive the king-bolt receptacle and on the back end the cross-piece D to receive the back spring. Tread *c* fastens parts 60 A together. The middle parts A form likewise a part of the fifth-wheel. Piece C, after being secured to B, completes the fifth-wheel.

Fig. 5 is the cage for friction-rollers, to be applied between the upper and lower part of 65 fifth-wheel. It consists of an inner ring *l* and outer ring *m*. These two rings are held concentric in position by braces *n* *n*, and both rings then fastened with arms *o* *o* to a plate *p*, through which the king-bolt *q* goes, and 70 thus the cage with friction-rollers works around the king-bolt, and around which also the fifth-wheel moves. As the diameter of the cage is made to suit the fifth-wheel, the rollers will reduce the friction which would 75 result if the two parts of the fifth-wheel were rubbing against each other, and consequently a light and easy movement is attained without the aid of grease.

I am aware that prior to my invention friction-rollers have been used, and do not claim the friction-rollers; but

What I claim as my invention, and desire to secure by Letters Patent, with friction-rollers combined, is—

1. The combination of middle pieces B, connected to rear piece D at one end and to the front piece at the other end, with the fifth-wheel having diverging curved ends, the side and back springs, and the axle, all arranged 90 as shown and specified.

2. In running-gear, the frame, formed of channel-iron, having the middle pieces, and the fifth-wheel provided with curved outward-diverging ends, and the friction-rollers, in 95 combination with the part D, front cross-piece, and plates *d* *d*, all as set forth.

HENRY WILLIAM FRACKMANN.
